WINDER.

1,366,447.

Specification of Letters Patent. Patented Jan. 25, 1921.

Application filed December 21, 1917. Serial No. 208,229.

To all whom it may concern:

Be it known that I, HOWARD D. COLMAN, a citizen of the United States, residing at Rockford, in the county of Winnebago and State of Illinois, have invented certain new and useful Improvements in Winders, of which the following is a specification.

The object of this invention, generally stated, is to provide improved means for counteracting any tendency that may be operating to make the yarn mass being wound eccentric or tapering. While the invention is applicable to various types of winders, it is herein shown as applied to a warping machine, such a machine being used in winding a considerable number of warp threads upon a section beam.

When the warper is to be operated at high speed, it is imperative that the yarn mass be prevented from becoming eccentric, as otherwise the bounding of the heavy beam will cause destructive vibration.

After being filled, the section beam is mounted with other section beams in a slasher, in the operation of which slasher the threads are rewound from the section beams onto a loom beam. If the yarn masses upon the section beams are tapering, the yarn will be rewound in the slasher with varying tension, causing serious trouble in the slasher and resulting in the production of imperfect warps.

In the accompanying drawings, Figure 1 is a fragmental side elevation of a warper embodying the features of my invention. Figs. 2 and 3 are sectional views showing the means whereby the beam is held in place in the warper, Fig. 2 being a view taken on dotted line 2-2 of Fig. 3, and Fig. 3 being taken on dotted line 3 of Fig. 1. Fig. 4 is a top plan view of the parts illustrated in Figs. 2 and 3. Fig. 5 is a fragmental view of a portion of the let-off mechanism. Fig. 6 is a horizontal sectional view through the warping machine showing the means for preventing non-cylindricity of the yarn mass. Fig. 7 is a sectional view showing certain gearing comprised in the mechanism. Fig. 8 is a detail view of a certain yoke and adjacent parts.

The beam B consists of a barrel having heads b' and trunnions b''. The beam is rotatable by means of a friction drum 122 rotatably supported in the framework of the warper and driven by any suitable means.

The beam is supported with its yarn mass in peripheral contact with the periphery of the driving drum 122 by means of two arms 120 pivoted to the warper framework upon the axis 121. The trunnions b'' may be connected to the arms 120 in any suitable manner. As the trunnions are sometimes out of alignment, it is desirable to provide a self-aligning connection between the trunnions and the arms 120. In the present construction, the free end of each arm 120 is provided with a socket 400 in its lower side to receive a ball member 401. The surface of the ball member 401 which makes contact with the socket 400 is a portion of a sphere. The socket 400 is made somewhat more than semi-circular to prevent the ball member 401 from falling out. Swivelling movement of the ball member may be limited in any desired manner, as, for example, by means of a stud 402 fixed to the socket and extending into an opening 403 in the ball member. The opening 403 is large enough to allow sufficient turning movement of the ball member.

Adjustably connected to the ball member 401 is a half-sleeve or bushing 404 fitting within an axial opening of the ball member and adapted to rest upon a trunnion b''. In order to keep the beam in proper longitudinal adjustment with reference to the driving drum 122, the bushing 404 of each arm 120 is caused to bear against an annular shoulder b''' on the trunnion by means of an adjusting screw 405 extending into the ball member 401. The bushing has a flange 406 which is secured to the adjusting screw 405 by means of a clamp 407.

A latch 408 is pivoted to each arm at 409, the free end of said latch being normally held in place beneath the trunnion b'' by means of a coiled spring 410. The latch is provided with a handle 411. The free end of the latch has a beveled edge 412 so that upon relative approaching movement between the arm 120 and the trunnion the latch shall be pushed aside to allow the trunnion to enter the bushing 404.

The arm 120 is connected to the pressure-applying means through the medium of a screw rod 413 extending through a slot 120* in the arm and carrying a nut 414 having diametrically opposite studs 415 that lie in elongated openings 416 in the arm. The screw rod 413 is rotatably mounted in a yoke or coupling member 417 (Figs. 1, 7 110

and 8) which is pivotally mounted upon a shaft 418 extending from side to side of the warper. The screw rod 413 is intermittently rotated to allow the arm 120 to rise 5 as the beam fills by means including a bevel gear 419 (Fig. 7) secured to the lower end of the screw rod, said bevel gear meshing with a similar gear 420 which is rigid with the shaft 418. It will be seen that the shaft 10 418 causes the screw rods 413 at the opposite sides of the warper to rotate simultaneously. As will be evident from Fig. 6, the rods 413 rotate in opposite directions, one rod having a right-hand thread and the other a left-hand thread.

The shaft 418 is rotatably mounted in bearings 421 (Fig. 7) in the forward ends of two levers 422, said levers being pivoted to the warper framework at 423. The rear 20 ends of the levers 422 carry roller studs 424 (Fig. 6) that lie within elongated openings in crank arms 425 fixed upon a rock-shaft 182. Rigid with the shaft 182 is a weighted arm 427 that causes a downward pull to be 25 exerted upon the screw rods 413.

The shaft 418 is rotated in the direction to cause the screw-rods 413 to travel downwardly in the nuts 414 by means comprising a ratchet wheel 428 (Figs. 5 and 7) 30 which is rigid with said shaft. Pivoted on the axis of the shaft 418 is an arm 429 having pivoted thereto a spring-pressed pawl 430 which is arranged to engage the ratchet wheel. The arm 429 is arranged to be 35 swung by means of a link 431 which is pivoted to a crank pin 432 upon one end of the shaft 433 of the friction drum 122. The link 431 has a longitudinal elongated opening 434 in which is located a roller stud 435 carried by the arm 429. A tension 40 spring 436 connected to the link and to said stud yieldingly connects the arm 429 to the link 431 and normally holds the stud 435 against the inner end wall of the 45 slot 434.

Rigid with the shaft 182 is a stop arm 437 (Fig. 1) which is arranged at times to obstruct the swinging movements of the arm 429 so as to prevent the pawl 430 from turning 50 the ratchet wheel. The arm 429 is provided with a bar 438 which is adapted to stop against the end of the arm 437.

Any suitable means may be provided to damp the vibrations of the weighted arm 55 427, as, for example, a dash-pot 439 (Fig. 1), the plunger of which is connected to one arm of a bell crank 440, the other arm of the bell crank having a pin-and-slot connection with an arm 441 that is rigid with 60 the arms 425 and 437.

In operation, the friction drum 122 is rapidly rotated to revolve the beam B in the direction to wind the warp threads thereon. The weighted arm 427 acting 65 through the shaft 182, the crank arms 425,

the levers 422, the yokes 417, the screw rods 413, the nuts 414, the studs 415 and the arms 120, presses the yarn mass on the beam tightly and practically unyieldingly against the drum 122. Any tendency operating to 70 make the yarn mass eccentric is continually being resisted. To illustrate: If the yarn mass were to become slightly eccentric, the high portion, in passing between the axes of the beam and the drum would tend 75 to force the arms 120 to swing away from the drum against the downward pull exerted through the screw rods 413, but by reason of the dash-pot 439 and the inertia of the parts, the arms 120 would not yield to such 80 upward pressure, and consequently the high portion would be rolled down, and the yarn mass restored to cylindrical form.

As the yarn mass increases in diameter, the arms 120 are forced upwardly, thus lifting 85 the screw rods 413, and causing the levers 422 to turn, the rear ends of said levers moving downwardly. As said levers are connected with the crank arms 425 and the latter in turn are rigid with the stop 90 arm 437, the forward end of said stop arm moves downwardly. When said stop arm has swung downwardly so far as to be entirely below the bar 438, the link 431 and 95 spring 436 are permitted to impart one or more complete oscillations to the arm 429, thereby enabling the pawl 430 to turn the ratchet wheel 428 through the distance of one or more teeth. The screw rods 413 are thereby turned through a partial revolution 100 in the direction to lower said rods. The rotation of the screw rods 413 allows the weighted arm 427 to descend, thereby swinging the stop arm 437 into the path of the bar 438, and causing a suspension of 105 operation of the pawl 430. The mechanism thus operates intermittently to adjust the connection between the arms 120 and the pressure-applying means as the yarn mass increases in diameter. Inasmuch as the 110 shaft 418 equalizes the rotation of the screw-rods 413 and the shaft 182 equalizes the movements of the levers 422, the upward movements of the opposite ends of the beam are parallel, and thus the formation of a 115 tapering yarn mass is prevented.

When the beam is to be removed from the warper, the arms 120 must be raised sufficiently to permit of the disengagement of the trunnions b^2 from the arms. After an 120 empty beam has been connected to the arms 120, said arms must be lowered to place the beam upon the drum 122. It is therefore desirable to provide means for manually rotating the screw rods 413 to raise and lower 125 the arms 120. The means herein shown for this purpose comprises a sprocket wheel 442 rotatably mounted upon one end frame of the warper and rigid with a crank-receiving stud 443. A chain 444 extends from the 130

wheel 442 to a wheel 445 (Fig. 7) which is rigid with the shaft 418. Rotation of the wheel 442 will raise or lower the arms 120. When the arms are to be lowered, the pawl 430 is held out of contact with the ratchet wheel.

The operation of connecting an empty beam to the arms 120 may be performed by one operative. One trunnion is first inserted into the bushing 404 of one of the arms 120, the ball 401 turning to align the bushing with the trunnion; and the latch 408 serving to hold the trunnion in place while the other trunnion is being lifted and connected to the other arm 120.

The invention is not limited to the construction and arrangement shown, as various modifications may be made within the scope of the invention as defined by the appended claims.

I claim as my invention:

1. A warper having, in combination, a framework, a driving drum rotatably mounted in the framework, two beam-supporting arms pivoted to opposite sides of the framework, two levers pivoted to opposite sides of the framework, a shaft supported by said arms, two coupling members on said shaft, a screw rod rotatably supported in each coupling member, a nut on each screw rod, said nuts bearing against said arms, means tending to move the levers in the direction to press the beam against the drum, a gear connection between said shaft and the screw rods, and yarn-controlled means for rotating the shaft.

2. A warper having, in combination, a framework, a driving drum rotatably mounted in the framework, two beam-supporting arms pivoted to opposite sides of the framework, two levers pivoted to opposite sides of the framework, a shaft supported by said arms, two coupling members on said shaft, a screw rod rotatably supported in each coupling member, a nut on each screw rod, said nuts bearing against said arms, means tending to move the levers in the direction to press the beam against the drum, a gear connection between said shaft and the screw rods, and means for rotating the shaft.

3. A winder having, in combination, a driving drum, a member for supporting the yarn mass in contact with the drum, means for pressing the yarn mass against the drum, a connection between the pressing means and the member, a ratchet wheel arranged to adjust the connection, a pawl for turning the ratchet wheel, an arm carrying the pawl, means yieldingly connected to the arm for reciprocating the latter, and a yarn-controlled member for obstructing the movement of said arm.

4. A winder having, in combination, a driving drum, a member for supporting a

yarn mass in contact with the drum, a lever, a screw rod connected to the lever, a nut on the screw rod, said nut bearing against said member, means tending to move the lever in the direction to press the yarn mass against the drum, a pawl and ratchet mechanism for rotating the screw rod, means tending to actuate the pawl, and yarn-controlled means for governing the pawl-actuating means.

5. A winder having, in combination, a driving drum, a member for supporting a yarn mass in contact with the drum, a lever, a screw rod connected to the lever, a nut on the screw rod, said nut bearing against said member, means tending to move the lever in the direction to press the yarn mass against the drum, a pawl and ratchet mechanism for rotating the screw rod, and means to actuate the pawl.

6. A winder having, in combination, a driving drum, a member for supporting a yarn mass in contact with the drum, a lever, a screw rod connected to the lever, a nut on the screw rod, said nut bearing against said member, means tending to move the lever in the direction to press the yarn mass against the drum, and yarn-controlled means for rotating the screw rod.

7. A winder having, in combination, a driving drum, a member for supporting a yarn mass in contact with the drum, a lever, a screw rod connected to the lever, a nut on the screw rod, said nut bearing against said member, means tending to move the lever in the direction to press the yarn mass against the drum, and means for rotating the screw rod.

8. A winder having, in combination, a driving drum, a member for supporting a yarn mass in contact with the drum, a screw rod, a nut on the screw rod, said nut bearing against said member, said screw rod resisting movement of the yarn mass away from the drum, and yarn-controlled means for rotating the screw rod.

9. A winder having, in combination, a driving drum, a member for supporting a yarn mass in contact with the drum, a screw rod, a nut on the screw rod, said nut bearing against said member, said screw rod resisting movement of the yarn mass away from the drum, and means for rotating the screw rod.

10. A winder having, in combination, a driving drum, a member for supporting a yarn mass in contact with the drum, a lever, a connection between the lever and said member, means tending to move the lever in the direction to press the yarn mass against the drum, and yarn-controlled means for adjusting the connection.

11. A winder having, in combination, a driving drum, a member for supporting a yarn mass in contact with the drum, a lever, a connection between the lever and said

- member, means tending to move the lever in the direction to press the yarn mass against the drum, and means for adjusting the connection.
- 5 12. A winder having, in combination, a driving drum, a member for supporting a yarn mass in contact with the drum, a lever, a screw and a nut connecting the lever to said member, means tending to move the 10 lever in the direction to press the yarn mass against the drum, and yarn-controlled means for rotating one of the two elements (namely, the screw and the nut) which connect the lever to said member.
- 15 13. A winder, having in combination, a driving drum, a member for supporting a yarn mass in contact with the drum, a lever, a screw and a nut connecting the lever to said member, means tending to move the 20 lever in the direction to press the yarn mass against the drum, and means for rotating one of the two elements (namely, the screw and the nut) which connect the lever to said member.
- 25 14. A warper having, in combination, a framework, a driving drum rotatably mounted in the framework, two beam-supporting arms pivoted to opposite sides of the framework, a nut connected to each 30 arm, a screw rod engaging each nut, means tending to pull the screw rods down, and means to effect the equal movement of said rods.
- 35 15. A warper having, in combination, a framework, a driving drum rotatably mounted in the framework, two beam-supporting arms pivoted to opposite sides of the framework, a rod connected to each arm at a point near the free end of the arm, 40 means tending to pull the rods down, and means to effect the equal movement of said rods.
- 45 16. A warper having, in combination, a framework, a driving drum rotatably mounted in the framework, two beam-supporting arms pivoted to opposite sides of the framework, a nut connected to each arm, a screw rod engaging each nut, means tending 50 to pull the rods down, and yarn-controlled means for rotating said rods.
- 55 17. A warper having, in combination, a framework, a driving drum rotatably mounted in the framework, two beam-supporting arms pivoted to opposite sides of the framework, a nut connected to each arm, a screw rod engaging each nut, means tending 60 to pull the rods down, and means for rotating said rods.
- 65 18. A winder having, in combination, a driving drum, a member for supporting a yarn mass in contact with the drum, means for pressing the yarn mass against the drum, a nut and a screw connecting said member to the pressing means, a pawl and ratchet mechanism for rotating one of said connect-
- ing elements, means tending to actuate the pawl, and yarn-controlled means for governing said pawl-actuating means.
19. A winder having, in combination, a driving drum, a member for supporting a 70 yarn mass in contact with the drum, means for pressing the yarn mass against the drum, a nut and a screw connecting said member to the pressing means, a pawl and ratchet mechanism for rotating one of said connecting elements, and means to actuate said mechanism. 75
20. A winder having, in combination, a driving drum, a member for supporting a 80 yarn mass in contact with the drum, means for pressing the yarn mass against the drum, a connection between the pressing means and the member, a pawl and ratchet mechanism for adjusting the connection, means tending to actuate the pawl, and 85 yarn-controlled means for governing said pawl-actuating means.
21. A winder having, in combination, a driving drum, a member for supporting a 90 yarn mass in contact with the drum, means for pressing the yarn mass against the drum, a connection between the pressing means and the member, a pawl and ratchet mechanism for adjusting the connection, and means to actuate said mechanism. 95
22. A winder having, in combination, a driving drum, a member for supporting a 100 yarn mass in contact with the drum, a nut connected to the member, a screw engaging the nut, means connected to the screw for pressing the yarn mass against the drum, a pawl and ratchet mechanism for rotating the screw, means tending to actuate the pawl, and 105 yarn-controlled means for governing said pawl-actuating means.
23. A winder having, in combination, a driving drum, a member for supporting a 110 yarn mass in contact with the drum, a nut connected to the member, a screw engaging the nut, means connected to the screw for pressing the yarn mass against the drum, a pawl and ratchet mechanism for rotating the screw, and means for actuating the pawl.
24. A winder having, in combination, a driving drum, a member for supporting a 115 yarn mass in contact with the drum, a nut connected to said member, a screw engaging the nut, means connected to the screw for pressing the yarn mass against the drum, and means for rotating the screw. 120
25. A winder having, in combination, a driving drum, a member for supporting a 125 yarn mass in contact with the drum, means for pressing the yarn mass against the drum, a nut and a screw connecting said member to the pressing means, and yarn-controlled means for rotating one of said connecting elements.
26. A winder having, in combination, a driving drum, a member for supporting a 130

5 yarn mass in contact with the drum, means for pressing the yarn mass against the drum, a nut and a screw connecting said member to the pressing means, and means for rotating one of said connecting elements.

27. A winder having, in combination, a driving drum, a member for supporting a yarn mass in contact with the drum, means for pressing the yarn mass against the drum, 10 a connection between the pressing means and the member, and yarn-controlled means for adjusting the connection.

28. A winder having, in combination, a driving drum, a member for supporting a 15 yarn mass in contact with the drum, means for pressing the yarn mass against the drum, a connection between the pressing means and the member, and means for adjusting the connection.

20 29. A warper having, in combination, a framework, a driving drum rotatably mounted in the framework, arms connected to the framework, each arm having a spherical socket, a ball mounted in the socket, and 25 a trunnion bearing connected to the ball for longitudinal adjustment.

30 30. A warper having, in combination, a framework, a driving drum rotatably mounted in the framework, arms connected 30 to the framework, each arm having a spherical

socket, and a ball mounted in the socket, said ball having a trunnion bearing.

31. A warper having, in combination, a framework, a driving drum rotatably mounted in the framework, arms connected 35 to the framework, and a trunnion-bearing swiveled to each arm.

32. A warper having, in combination, a framework, a driving drum rotatably mounted in the framework, an arm connected to the framework for supporting a beam in contact with the drum, means connected to said arm for holding the beam pressed against the drum, said means including two interengaging elements one of 40 which is rotatable, and yieldable means preventing rotation of said rotatable element.

33. A warper having, in combination, a framework, a driving drum rotatably mounted in the framework, two arms connected 45 to the framework and having downwardly-opening sockets to receive the trunnions of a beam so as to support it in operative association with the driving drum, and latches on the arms to lie beneath the trunnions and thus prevent disengagement of 50 the arms from the trunnions.

In testimony whereof I have hereunto set my hand.

HOWARD D. COLMAN.
